SEMISUBMERSIBLE MOTOR PUMP

Aladar Hollander, Berkeley, Calif., assignor to
 Byron Jackson Co., Huntington Park, Calif.,
 a corporation of Delaware

Application April 5, 1937, Serial No. 135,059

5 Claims. (Cl. 103—87)

This invention relates to motor driven pumps for raising liquid from wells, and more particularly to that form of pumping unit in which the motor and pump are both placed in the well at or near the fluid level. The pumps employed for this purpose are usually (but not necessarily) centrifugal pumps. Electric motors are used to drive the pumps.

Motor-pump units as heretofore used in the foregoing manner have been of three general types:

(1) That type in which the motor is at the top of the well and is connected by means of a long shaft to the pump below the fluid level. The objection to this type of construction is the cost of the long drive shaft and the amount of power required to drive it.

(2) That type in which both the motor and pump are submerged below the draw-down fluid level in the well. With this type of construction it is very difficult and expensive to provide a motor construction which will positively prevent the entrance of well fluid into the interior of the motor.

(3) That type in which the pump is below the fluid level in the well while the motor is above the fluid level and is suspended from the discharge column, a cable or a packer set in the well casing. With this type of construction it has been necessary to raise or lower the pumping unit from time to time as the fluid level varies in the well. Moreover, it has been the custom to conduct the fluid from the pump through a discharge pipe past the motor and thence to the discharge column. Because of the small diameter of most wells it is impossible to use a motor of reasonably large diameter when room must be left between the motor and well casing for the discharge pipe. Motors of small diameter must be made very long in order to develop the required power, thus entailing special expensive manufacturing facilities. Moreover, small diameter motors are not as readily cooled by air as are larger diameter motors.

It is an object of present invention to provide a motor pump unit which can be placed at or near the fluid level in a well in order to eliminate the long drive shaft between the motor and pump.

Another object is to provide a construction whereby the motor is at all times above the fluid level in the well.

Another object is to provide a motor-pump unit in which the motor, although above the pump, is of relatively large diameter as com-

pared to the diameter of the casing in which it is placed.

Another object is to provide a construction wherein the motor is cooled by the pumped fluid but without the necessity of using special means for excluding well fluid from the motor as is necessary with true submersible motor-pumps.

Another object is to utilize the pump discharge column to suspend the motor-pump unit in the well.

The foregoing and other advantages will be apparent from the following description and drawing.

Figure 1 is an elevation, partly in cross section, of the upper half of a motor-pump embodying the invention as installed in a deep well.

Figure 2 is an elevation, partly in cross section, of the lower half of the motor-pump shown in Fig. 1.

The numeral 1 indicates the casing of a well. The standing fluid level in the well is indicated at 3 and the pumping fluid level at 4. The difference between these two levels is commonly called the draw-down.

A typical deep well centrifugal pump is indicated at 6 positioned below the lowest fluid level in the well. The pump suction is indicated at 7.

The electric motor which drives the pump is enclosed in a fluid tight housing indicated at 9 positioned above the highest fluid level in the well.

The motor is connected to the pump 6 by means of a shaft 11. This shaft is of a length somewhat greater than the normal draw-down of the well (which is as a rule much less than the distance to the top of the well).

Above and secured to the discharge end of the pump 6 is a flanged top case 12 bolted to the pump casing at one end and bolted to an adapter case 13 at its other end. The top case 12 is provided with a stuffing box 14 and a plain bearing 15. Threadedly connected to the upper end of the adapter case 13 is a short section of pipe column 16 the upper end of which is threadedly connected to an adapter case 17. Supported upon the upper end of the case 17 is a by-pass conduit 18 having a substantially semi-annular fluid passage 19 off-set laterally from the vertical axis of the shaft 11. The lower end of conduit 18 is provided with an opening 20 through which the motor shaft passes. The upper end of the by-pass conduit 18 is provided with a laterally extending flange 21 having an opening 22 through which the motor shaft passes. A tube 23 encloses the shaft 11 between the lower end of the case 17 and the upper end of the adapter case 13.

17 and the upper end of the bearing 15. This tube is adapted to be filled with lubricant for the pump bearing 15 from a pipe 24 which may extend to the surface of the well. The tube 23 extends through the opening 20 and is threadedly supported from a nut 23a which rests on the by-pass conduit 18. A cover 23b rests upon the top of the nut 23a and is provided with a threaded opening 23c adapted to receive the oil pipe 24.

10 Supported on and extending upwardly from the flange 21 is a cylindrical casing 25 which surrounds the motor casing 9 and provides an annular fluid passage 26 between the two casings. The upper end of casing 25 is provided with a cover 27 provided with two openings, 28 and 29. An extension 33 on the top of the motor casing 9 extends through the opening 28 and is secured in fluid tight relation thereto by means of a suitable packing 30, a follower ring 31 and a sleeve 20 32 threadedly engaging the upper end of extension member 33. The motor leads 34 pass through the extension member 33 and out through a stuffing box 35 and thence to the top of the well. The cover 27 is provided with a by-pass conduit 25 36 having a semi-annular fluid passage 37. The upper end of the by-pass conduit 36 is provided with a laterally extending flange 38. An adapter casing 39 is supported on the flange 38 and is threadedly connected to the lower end of the discharge casing 40.

30 From the foregoing description it will be seen that the fluid discharged upwardly from the pump 6 passes through the pipe 16, the by-pass 18, the annular channel 26 between the casings 9 and 25, the by-pass 36 and thence upward through the discharge column 40 to the top of the well. The fluid serves to cool the motor housing 9 thereby increasing the efficiency of the motor and making practical the use of relatively small diameter motors, and at the same time permitting the use of motors of relatively large diameter as compared to the diameter of the well casing.

45 There is no danger of well fluid getting into the motor housing 9 because the motor housing is placed well above the maximum standing fluid level 3 and because both ends of the motor are sealed from the well fluid but are open to the air space in the well. Consequently it is not necessary to use a motor of the so-called "submersible" type, that is, a motor having means for preventing the entrance of well fluid into the motor. The present construction therefore becomes economical since it permits the use of air-filled motors of the conventional type.

50 Inasmuch as the pump 6 is placed well below the lowest pumping water level and the shaft 11 is longer than the normal draw-down, there is no need to change the pump setting during normal conditions, and yet the shaft 11 is relatively short and inexpensive as compared to the shaft of the conventional pump which extends from below the lowest fluid level to the top of the well.

55 The pump and motor are supported in the well by being suspended from the discharging column.

I claim:

1. In a deep well pump for wells having a substantial draw-down, a discharge column extending from the top of the well to a point adjacent but above the maximum normal fluid level in the well, a casing suspended from said discharge column and in open communication therewith, a housing containing an electric motor mounted in said casing in spaced relation to the walls thereof and in fluid tight relation thereto and adapted to be cooled by the fluid passing through

said casing, said housing being located in fixed position above said maximum normal fluid level and the interior thereof being in communication with the air space in the well, a second discharge column suspended from said casing and in open communication therewith, said second column being of a length greater than the draw-down of the well, a rotary pump supported from said second discharge column and having its suction inlet positioned below the lowest normal fluid level in the well, and a shaft connecting said pump and said motor.

2. In a deep well pump for wells having a substantial draw-down, a discharge column extending from the top of the well to a point adjacent but above the maximum normal fluid level in the well, a casing suspended from said discharge column, a fluid conduit communicating the upper end of said casing with the lower end of said discharge column, said conduit being offset laterally from the vertical axis of said casing, a housing containing an electric motor mounted in said casing in spaced relation to the walls thereof and in fluid tight relation thereto and adapted to be cooled by the fluid passing through said casing, the ends of said housing extending through the ends of said casing at the vertical axis thereof, said housing being located in fixed position above said maximum normal fluid level and the interior thereof being in communication with the air space in the well, a second fluid conduit secured to the lower end of said casing in an offset relation to the vertical axis thereof, an extension pipe secured to the lower end of said second conduit in line with the vertical axis of said motor, said second fluid conduit and said extension pipe being of a combined length greater than the draw-down of the well, a rotary pump secured to the lower end of said extension pipe and positioned with its suction inlet below the lowest normal fluid level in the well, and a drive shaft extending from said motor to said pump.

3. In a deep well pump for wells having a substantial draw-down, a discharge column extending from the top of the well to point adjacent but above the maximum normal fluid level in the well and concentric with respect to the vertical axis of the well, a casing suspended from said discharge conduit in axial alignment therewith, a housing containing an electric motor mounted in said casing in spaced relation to the walls thereof and in fluid tight relation thereto and adapted to be cooled by the fluid passing through said casing, the interior of said housing being in communication with the air space in the well, said motor housing being located in fixed position above the maximum normal fluid level in the well, a conduit communicating said casing with said discharge column and offset laterally from the vertical axis thereof, a second discharge column suspended from said casing and in open communication therewith, said second column being of a length greater than the draw-down of the well, a rotary pump suspended from said second discharge column and having its discharge outlet in open communication therewith, said pump being positioned with its suction inlet below the lowest normal fluid level in the well, and a drive shaft connecting said pump and motor.

4. In a deep well pump as defined in claim 1, motor leads extending from the upper end of the motor housing at a point outside the casing, the lower end of said motor housing having an

- opening to the air space in the well, the shaft extending through said opening.
5. In a deep well pump for wells having a substantial draw-down, a discharge column extending from the top of the well to a point adjacent but above the normal fluid level in the well, a casing suspended from said discharge column and in open communication therewith, a housing containing an electric motor mounted in said 10 casing in spaced relation to the walls thereof and in fluid tight relation thereto and adapted to be cooled by the fluid passing through said casing, the interior of said housing being in communication with the air space in the well and

said housing being located in fixed position above said maximum normal fluid level, a pipe communicating at its upper end with said casing and extending to a point below the lowest normal fluid level in the well, a rotary pump suspended 5 from said pipe and adapted to discharge well fluid into the lower end thereof, a shaft extending through said pipe and operatively connecting said motor and pump, a bearing at the lower end of said shaft, a tube surrounding said shaft in 10 spaced relation thereto and spaced from the walls of said pipe, and means for supplying lubricant to said tube.

ALADAR HOLLANDER.
